EVERETT E. CLARK, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME BRACKET.

Application filed March 26, 1927. Serial No. 178,785.

This invention relates to a tube frame bracket, such as is commonly used in Axminster carpet looms. These brackets are used for supporting the yarn tubes and spools and for attaching the same to the transporting pattern chains.

It is the object of my invention to improve the construction of such tube frame brackets and particularly to provide an improved form of spring which will be more reliable and effective in use and less subject to accidental breakage.

My invention further relates to arrangements and combinations of parts which will be hereinafter described and more particularly pointed out in the appended claims.

Two forms of the invention are shown in the drawings in which—

Fig. 1 is a sectional front elevation of a portion of a tube frame and bracket embodying my improvements;

Fig. 2 is an end elevation of the bracket, looking in the direction of the arrow 2 in Fig. 1;

Fig. 3 is a sectional plan view, taken along the line 3—3 in Fig. 1;

Fig. 4 is a sectional front elevation of a modification; and

Fig. 5 is a sectional plan view, taken along the line 5—5 in Fig. 4.

Referring particularly to Figs. 1 to 3, I have indicated a portion of a rectangular metallic tube frame 10 having a series of yarn tubes 11 secured thereto. Tube frame brackets are mounted in each end of the tube frame 10 and each bracket comprises an L-shaped bearing member 12 having an opening 13 in its upper end for the gudgeon of a yarn spool S. A second or outer portion 14 of the bracket is permanently secured to the portion 12 by welding or other suitable means, and has an offset portion 15 adapted to extend upward between the links 16 of a transporting pattern chain. The lower end portions 17 and 18 of the members 12 and 14 are offset laterally and extend in parallel relation within the tube frame 10.

A U-shaped member 20 is fitted between the offset portions 17 and 18 and at its outer end abuts the inner face of the member 14. The member 20 is displaced inwardly, as indicated at 22, to provide a bearing for a cross

pin 23 and the upper leg of the member 20 has a reversely curved portion 24 to provide a recess 24^a for a purpose to be described. 55

The member 14 is slotted at 25 and 26 to receive a spring hook 30 and the member 20 is slotted at 31 for the same purpose. The hook 30 has a reverse bend at its lower end and is also offset laterally so that it presents a substantially L-shaped outline when in operative position.

The U-shaped member 20 is preferably permanently secured between the members 12 and 14 in some convenient manner as by welding thereto. Screws 33 are provided to secure the bracket to the tube frame and these screws are preferably extended into the member 20 and form an additional securing means therefor. 70

The parts are assembled by inserting one end of the spring 30 through the slot 25 and the other end of the spring through the slots 26 and 31, pushing the spring inward until the extreme end of its lateral projection is received in the recess 24^a formed by the reverse bend 24. The cross pin 23 is then inserted, retaining the spring firmly in position. The abrupt upward turn of the spring 30 at the point 35 provides a shoulder which 75 engages the cross pin 23 and prevents outward displacement of the spring.

When a tube frame is attached to or detached from a transporting chain, the spring hook 30 is pushed away from the chain 16 over a substantial range of movement. This repeated bending movement has frequently caused breakage in the springs heretofore used. With my improved construction, however, the bending movement is distributed 80 over a much greater length of resilient material and is not localized at a single point, as was the case when the springs were secured by screws to the outer face of the bracket.

In Figs. 4 and 5, I have shown a somewhat simpler construction in which the bracket members 40 and 41 are substantially similar to those previously described, the outer member 41 being provided with slots 42 and 43 and having a reversed inner end portion 44 95 providing a recess 45 to receive the inner end of a spring hook 46. The hook 46 extends through the slots 42 and 43 and is retained in position by a cross pin 47 inserted 100

through the side walls of the tube frame 48, after assembly of the bracket therein.

The spring 46 has a laterally curved portion 49 engaging the upper end of the slot 43 and preventing upward displacement of the hook. The spring 46 also has a downwardly curved portion 50 abutting the cross pin 47 and preventing outward displacement of the spring, after the pin 47 is inserted. 10 This form of my invention is somewhat simpler than that previously described and retains many of the advantages thereof.

Having thus described my invention and the advantages thereof, I do not wish to be limited to the details herein disclosed otherwise than as set forth in the claims, but what I claim is:—

1. In a loom, a rectangular yarn tube frame, and a tube frame bracket comprising 20 and L-shaped spool-supporting member, an L-shaped chain-engaging member having upper and lower slots therein, said members being permanently secured together and having their parallel offset lower end portions 25 extending within said tube frame, and a chain-engaging spring hook of general L-shape formation mounted in said bracket and having its offset lower end extending freely a substantial distance within said tube 30 frame and secured at its inner end in substantially fixed relation to said tube frame bracket, said spring being free to flex throughout substantially its entire length.

2. In a loom, a rectangular yarn tube frame, and a tube frame bracket comprising 35 an L-shaped spool-supporting member, an L-shaped chain-engaging member having upper and lower slots therein, said members being permanently secured together and having 40 their parallel offset lower end portions extending within said tube frame, and a substantially L-shaped angularly movable chain-engaging hook extending through said upper and lower slots and having its lower end extending freely a substantial distance within 45 said tube frame and positively held from outward displacement therein, said spring being free to flex throughout substantially its entire length.

3. In a loom, a rectangular yarn tube frame, and a tube frame bracket comprising 50 an L-shaped spool-supporting member, an L-shaped chain-engaging member having upper and lower slots therein, said members being permanently secured together and having 55 their parallel offset lower end portions extending within said tube frame, and a chain-engaging spring hook of general L-shape formation extending through the upper and lower slots in said chain-engaging member 60 and having its offset lower portion extended freely a substantial distance within said tube frame, and means to prevent outward displacement of said spring hook, the inner end of said spring hook being positioned in a 65 recess at the inner end of said bracket and being held under tension thereby, and said spring being free to flex throughout substantially its entire length.

4. In a loom, a rectangular yarn tube frame, said spring being free to flex throughout substantially its entire length.

5. In a loom, a rectangular yarn tube frame, and a tube frame bracket comprising an L-shaped spool-supporting member, an L-shaped chain-engaging member having upper and lower slots therein, said members being permanently secured together and having their parallel offset lower end portions extending within said tube frame, and a substantially L-shaped chain-engaging spring hook extending through said upper and lower slots and pivotally mounted at the end of said tube frame and having its offset lower end extending freely a substantial distance within said tube frame and positively held from vertical displacement therein, said spring being free to flex throughout substantially its entire length.

5. In a loom, a rectangular yarn tube frame, and a tube frame bracket comprising an L-shaped spool-supporting member, an L-shaped chain-engaging member having upper and lower slots therein, said members being permanently secured together and having their parallel offset lower end portions extending within said tube frame, and a substantially L-shaped chain-engaging spring hook extending through said upper and lower slots and pivotally mounted at the end of said tube frame and having its offset lower end extending freely a substantial distance within said tube frame and positively held from vertical displacement therein, said spring being free to flex throughout substantially its entire length.

6. In a loom, a rectangular yarn tube frame, and a tube frame bracket comprising an L-shaped spool-supporting member, an L-shaped chain-engaging member having upper and lower slots therein, said members being permanently secured together and having their parallel offset lower end portions extending within said tube frame, a chain-engaging spring hook of general L-shape formation extending through the upper and lower slots in said chain-engaging member 115 and having its offset lower portion extended freely a substantial distance within said tube frame, and means to prevent outward displacement of said spring hook, the inner end of said spring hook being positioned in a 120 recess at the inner end of said bracket and being held under tension thereby, and said spring being free to flex throughout substantially its entire length.

7. In a loom, a rectangular yarn tube frame, and a tube frame bracket comprising an L-shaped spool-supporting member, an L-shaped chain-engaging member having upper and lower slots therein, said members being permanently secured together and having 130

their parallel offset lower end portions extending within said tube frame, a U-shaped spring-retaining member secured between said parallel offset portions and having a 5 reversely bent inner end portion, and a chain-engaging spring hook having an offset lower end, said hook extending through the upper and lower slots in said chain-engaging member and within said tube frame and being retained 10 from outward displacement therein and said spring hook being held under tension by engagement of the inner end of its offset portion with the reversely bent portion of said spring-retaining member, and said 15 spring being free to flex throughout substantially its entire length.

8. In a loom having a rectangular hollow tube frame, a tube frame bracket comprising

a rigid structure having upper and lower portions extending within said tube frame, one 20 of said portions having a recess substantially within said hollow tube frame and on the side of said portion toward the center line of said tube frame, said recess facing the open end of said tube frame, and a spring hook 25 mounted in said bracket and having a portion extending substantially within said tube frame and having its inner end seated in said recess, said spring being thereby held under tension and held from vertical displacement 30 and said spring being free to flex throughout substantially its entire length.

In testimony whereof I have hereunto affixed my signature.

EVERETT E. CLARK.
